United States Patent Office

Des. 200,566
Patented Mar. 16, 1965

200,566

BEVERAGE DISPENSER

Joseph R. Mango, Midlothian Country Club Grounds,
14651 S. 49th Court, Midlothian, Ill., and Robert M.
Goodman, 9024 Moody Ave., Morton Grove, Ill.

Filed Nov. 14, 1963, Ser. No. 77,419

Term of patent 14 years

(Cl. D2—3)

FIG. 1

FIG. 2

FIG. 5

FIG. 3

FIG. 4

FIG. 1 is a perspective view taken from the left and slightly above the beverage dispenser showing our new design;

FIG. 2 is a front elevational view thereof;

FIG. 3 is a side elevational view of the right side of the beverage dispenser showing our new design, the opposite side being substantially a mirror image thereof;

FIG. 4 is a bottom view thereof; and

FIG. 5 is a rear elevational view thereof.

We claim:

The ornamental design for a beverage dispenser, as shown and described.
